UNITED STATES PATENT OFFICE

127,886

DESIGN FOR A BROOCH OR SIMILAR ARTICLE

Walter L. Pavel, Chicago, Ill.

Application March 24, 1941, Serial No. 99,823

Term of patent 3½ years

To all whom it may concern:

Be it known that I, Walter L. Pavel, a citizen of the United States, residing at Chicago, in the county of Cook and State of Illinois, have invented a new, original, and ornamental Design for a Brooch or Similar Article, of which the following is a specification, reference being had to the accompanying drawing forming a part thereof, in which:

Figure 1 is a front elevational view of a brooch showing my new design; Figure 2 is a side elevational view of the same; and Figure 3 is a top plan view.

I claim:

The ornamental design for a brooch or similar article, as shown.

WALTER L. PAVEL.
